JEROME REDDING, OF CHARLESTOWN, AND JOHN B. COE, OF BOSTON,
MASSACHUSETTS.

Letters Patent No. 76,813, dated April 14, 1868.

IMPROVED PASTRY-JIGGER.

The Schedule referred to in these Letters Patent and making part of the same.

TO ALL WHOM IT MAY CONCERN:

Be it known that we, JEROME REDDING, of Charlestown, Middlesex county, and JOHN B. COE, of Boston, Suffolk county, all in the State of Massachusetts, have invented an Improved Pastry-Jigger; and we do hereby declare that the following, taken in connection with the drawings which accompany and form part of this specification, is a description of our invention sufficient to enable those skilled in the art to practise it.

The invention relates to the construction of an instrument called a "pie or pastry-jigger," the purpose of which is to ornament the edges of pies and other pastry, such instrument having a rotary wheel with peripheral teeth, the rotation of this wheel around the edge of the pie or piece of pastry making the indentations by which the edge of the pastry is ornamented.

These wheels have heretofore been put upon the extreme end of the instrument; and to keep the wheel at an even distance from the edge of the pastry or pie-plate, requires some considerable skill; and the object of our invention has been to so construct a pastry-jigger that it could be guided without skill, or so as to make a uniformly concentric circle of indentations in the surface of the paste.

Our invention consists in a pastry-jigger having a circumferential marker, the operative face of which is notched or grooved, to produce ornamental markings, and is substantially at right angles with a shank, which is provided at one end with a notched or ornamental marker, which serves the purpose of a gauge to guide the other marker, so as to cause the indented path thereby made to be parallel with the edge against which the marking-gauge is kept in contact.

The drawings represent an instrument embodying our improvement.

A shows a front view of the "jigger."

B, a side or edge view thereof.

a denotes the shank of the instrument, having the marker-wheel b at or near one end thereof, while its opposite end may have lateral projections c, cut out on the lower surface, with an ornamental design to make detached imprints upon the surface of the pastry.

The wheel b is mounted loosely on a pin, d, projecting from an extension, e, from the shank, and this extension continues beyond the wheel, making a guide, f, for running against the edge of the plate, and for thereby keeping the wheel at a uniform distance from such edge, as its teeth g roll around the piece of pastry, as before set forth.

This guide may be made plain, or it may branch laterally, and be furnished with teeth h, to indent the paste.

With the jigger thus made, pastry can be much more expeditiously and uniformly ornamented than with pastry-jiggers as now in common use, and this without any skill other than that required to pass the instrument around a plate.

We claim, as a new article of manufacture, a pastry-jigger made up of a circumferential marker, b, and a shank, which, while operating as a gauge, is notched, so as also to serve as a marker, as described.

JEROME REDDING,
JOHN B. COE.
